(57) **CLAIM**

The ornamental design for an indexable cutting insert, as shown.

DESCRIPTION

FIG. 1 is a view of an indexable cutting insert showing our new design;

FIG. 2 is a top plan view of the insert of FIG. 1; and,
FIG. 3 is a side view of the insert of FIG. 1.

The broken line showing is for illustrative purposes only and forms no part of the claimed design.
